UNITED STATES PATENT OFFICE

LOUIS TRNOVEC, OF WILLOW SPRINGS, ILLINOIS

TOOTHPICK DISPENSER

Application filed March 31, 1928. Serial No. 266,232.

This invention relates to improvements in toothpick dispensing devices and has among its objects to provide a new, useful and sanitary device which is adapted to hold a quantity of toothpicks and which is provided with 5 manually operable means for delivering or discharging one toothpick at a time from the storage hopper therein.

It is also an object of the invention to provide a delivery mechanism for a tooth pick 10 storage hopper which is arranged to receive and discharge only one toothpick during each cycle of operation thereof.

Another object of my invention is found in the provision of a toothpick feed comprising a pair of segmental arcuate discharging members provided with longitudinally extending integral ledges adapted upon oscillation in one direction to receive a single toothpick and to discharge said toothpick 20 when oscillated in the opposite direction.

A further object of my invention is found in the pivotal mounting of such arcuate segmental discharging members and inter-connecting means whereby such members and their integral ledges are always moved in opposite directions.

A still further object is found in the adaptation of an arcuate segmental pivotally mounted retaining member having an upstanding longitudinally extending edge and which retaining member is adapted to be loosely mounted over one of said adjacent discharging members and arranged to positively control the gravity discharge of the toothpicks 30 by retaining the toothpick following the one about to be discharged. The retaining member being resiliently held against movement in one direction and operatively connected to its adjacent discharging member.

Still another object of my invention resides in the provision of a fourth arcuate segmental member resiliently held in forward position, loosely mounted over the other of said discharging members and arranged to move slightly the pressure of its spring in case a toothpick of abnormal cross section is engaged by the retaining member.

With above and other objects in view, 40 my invention consists in the novel combina-

tion, construction and arrangement of the parts and members shown in the preferred embodiment in the accompanying drawings, described in the following specifications and particularly pointed out in the appended 55 claims.

Referring to the illustrations:

Fig. 1, is a front elevation of a toothpick dispenser embodying my invention and Fig. 2, is a side elevation thereof with parts broken 60 to show details.

Fig. 3, is a vertical section taken on line 3—3 of Fig. 1, showing the interior thereof, the feed mechanism being shown in charging position.

Fig. 4, is a view similar to that shown in Fig. 3, but with the feed mechanism shown in discharging position.

Fig. 5, is a vertical section taken on line 5—5 of Fig. 3.

Fig. 6, is a cross section taken on line 6—6 of Fig. 3.

Fig. 7, is another view similar to that shown in Figs. 3 and 4, but showing the feed mechanism in normal position after receiving the 75 toothpick which is about to be discharged.

Referring now to the several illustrations, a casing 10 is provided of rectangular cross section having the lower ends 10^a of two opposite walls deflected toward each other to 80 form a discharge spout having an elongated discharge opening 10^b. A pair of plates 11 and 12 are provided to form the bottom of a storage hopper 13 for the toothpicks. The plates 11 and 12 also being deflected at their 85 lower ends toward each other to form an elongated discharge opening 13^a substantially in vertical alignment above the casing discharge opening 10^b. A cover 10^c is provided 90 for the open upper end of the casing 10.

The casing 10 may be supported or mounted in any suitable way; I have here shown a curved rod 16 and a base 17 therefor.

A pair of shafts 14 and 15 are provided, 95 which are supported for oscillation in the side walls of the casing 10. The ends of these shafts is extended beyond one side of the casing upon which are rigidly mounted intermeshing gear segments 14^a and 15^a. The 100

shaft 14 extends beyond the gear segment 14^A to receive an operating wheel 14^B.

Within the casing 10 and below the hopper discharge opening 13^A, I provide a pair of discharging members 18 and 19, rigidly mounted upon respective shafts 14 and 15 and oscillatable therewith. The discharging members comprise segmental arcuate walls 18^A and 19^A with integral longitudinally extending ledges 18^B and 19^B respectively at adjacent sides thereof and extending the full length of the walls. The walls 18^A and 19^A are provided at their ends with downwardly disposed integral ears 18^C and 19^C which rigidly engage their respective shafts 14 and 15.

15 A second pair of members 20 and 21 are provided which I term "retaining members", as their function is the retaining of the toothpicks following the one engaged by the discharging members. The retaining members 20 and 21 are formed with respectively arcuate segmental walls 20^A and 21^A which overlay the walls 18^A and 19^A and which are also provided with downwardly disposed integral ears respectively 20^C and 21^C. The ears 20^C and 21^C being however loosely mounted on the shafts 14 and 15.

20 The wall 21^A is provided with an integral upstanding edge 21^B adapted to engage and retain a follower toothpick against the wall 20^A during the discharge operation of the members 18 and 19.

25 The retaining members are held in operative position by means of leaf springs 22.

30 When the discharging members 18 and 19 are moved to their uppermost position as shown in Fig. 3, the edge 21^B will be raised to permit the follower toothpick to fall upon the ledges 18^B and 19^B. The movement of the member 21 and its edge 21^B to such upper position is made possible by the provision of the pin 19^D mounted within the wall 19^A which operates within the slot 21^D of the member 21. When the wheel 14^B is turned 35 to move the members 18 and 19 upwardly, the pin 19^D will at a certain time reach the end of the slot 21^D and cause an oscillation of the member 21 toward the right (as viewed in Figs. 3 and 4) against the pressure of 40 spring 22 which is attached thereto and when the hand wheel 14^B is released the spring 22 will cause a reverse movement of the member 21 to thereby engage a follower toothpick by the edge 21^B and retain same against the wall 20^A of the member 20, and during such movement, the members 45 18 and 19 will be brought into neutral position as shown in Fig. 7, with a toothpick supported on the ledges 18^B and 19^B in position 50 to be discharged, which may readily be done by movement of the handwheel 14^B to cause a downward and separating movement of the ledges 18^B and 19^B, as shown in Fig. 4. An opposite oscillation of the handwheel 14^B 55 will then again bring the parts and members

to their positions shown in Fig. 7, where the next or follower toothpick is released for passage onto the ledges 18^B and 19^B of the discharging members 18 and 19.

60 It may here be stated that if a toothpick of abnormal oversize cross section should be engaged by the retaining edge 21^B, the member 20 being loosely supported on shaft 14 and resiliently held in position, will readily give and thus avoid any inoperation of the discharging members 18 and 19 when moved into discharging position with the pin 19^D in the opposite end of the slot 21^D pressing against the member 21 to retain the follower toothpick.

65 An agitator and toothpick straightener is provided in the form of an arcuate plate 23 having an integral side 23^A bent angularly to form an arm pivotally and rigidly mounted on the shaft 24 on one end of which is rigidly mounted the operating arm 25. The arm 25 is provided with a slot 25^A. The gear segment 14^A is provided with an integral extension 14^C having a pin 14^D which engages within this slot 25^A to thereby cause an oscillation of the arm 25 and plate 23 through the mass of toothpicks when the device is operated.

70 A cover 26 may be provided over the gear segments 14^A and 15^A and arm 25.

I claim:

75 1. A toothpick dispensing device including a storage hopper for the toothpicks having an elongated discharge opening, a manually operable feed mechanism oscillatably supported below said hopper discharge opening comprising a pair of coacting supports adapted upon oscillation in one direction to receive a single toothpick from said hopper opening and to discharge said single toothpick upon a reverse oscillation thereof, and means for retaining the toothpick adjacent to the one to be discharged in a position to be received by said coacting supports upon the discharge of the toothpick supported thereon and the return of said coacting supports into receiving position.

80 2. A toothpick dispensing device including a toothpick storage hopper having an elongated discharge opening, a manually operable oscillatable feed mechanism supported below said hopper discharge opening comprising a pair of oscillatable shafts, a toothpick discharging member rigidly mounted on each of said shafts, each of said discharging members having a toothpick supporting ledge said ledges being arranged adjacent to one another and adapted upon the oscillation of said member in one direction to receive a single toothpick thereon from said hopper opening and to discharge the received toothpick upon the reverse oscillation of said members, means operatively interconnecting said shafts for simultaneously oscillating said shafts, and means for retaining and control-

ling the discharge of the toothpicks from said hopper opening operatively responsive to the oscillation of said discharging members whereby only one toothpick will be discharged from said hopper opening to said ledges of said discharging members during a cycle of operation.

3. A toothpick dispensing device as embodied in claim 2, wherein said shaft interconnecting means comprises a pair of gear segments.

4. A toothpick dispensing device as embodied in claim 2, wherein said means for retaining and controlling the discharge of the toothpicks from said hopper opening comprises an oscillatably supported member, a spring for retaining said retaining and controlling oscillatably supported member in retaining position, and means associated with one of said discharging members for moving said retaining and controlling member against the pressure of said spring into release position to release the retained toothpick for gravity discharge onto said ledges.

25 5. A toothpick dispensing device as embodied in claim 2, wherein said means for retaining and controlling the discharge of the toothpicks from said hopper opening comprises an oscillatably supported member, a spring for retaining said retaining and controlling oscillatably supported member in retaining position, means associated with one of said discharging members for moving said retaining and controlling member against the pressure of said spring into release position to release the retained toothpick for gravity discharge onto said ledges, and an oscillatable spring pressed support co-operating with said retaining and controlling member 30 for supporting a toothpick during the receiving and discharging operation of said discharging members, said spring pressed support being adapted to move against the pressure of its spring to provide clearance 35 for supporting a toothpick of abnormally increased cross section.

In witness whereof I affix my signature.
LOUIS TRNOVEC.
